PUNCHING MACHINE

Frederick L. Fuller, West Orange, N. J., assignor
to International Business Machines Corpora-
tion, New York, N. Y., a corporation of New
York

Application August 16, 1938, Serial No. 225,084

8 Claims. (Cl. 164—112)

This invention relates to punching machines which are capable of perforating records such as tabulating cards to represent data pertaining to a sale. More specifically, the invention relates to machines of the manually controlled type, whereby the operator may predetermine the data to be punched upon the tabulating card, so that for each operation of the machine a card will be punched so as to be capable of controlling tabulating and statistical machines of a type now on the market.

The present machine is specifically designed for use in connection with mercantile establishments known as co-operative stores and which stores are primarily concerned with the selling of articles such as food, clothing, etc. Stores of this type dispense or sell articles which are purchased in the usual manner and distinguish from other types of stores such as independently operated stores, or chain stores, in that the profit made by a group of co-operative stores is returned as dividends to the customers in amounts commensurate with the amount of the purchases made by the respective customers. Each store has a number of customers dealing with that particular establishment and these customers are generally known as "members" and for each member an account number is allocated. Obviously, the amount of profit which is returned at the end of a period to the different members is based upon the amount of purchases made by that customer. It has been the practice to utilize printed or written slips in the accounting operations to determine such statistics, and if performed with the aid of customary bookkeeping methods, it is a very laborious task entailing a great deal of time and requiring many adding machines and persons for accomplishing this procedure. This accounting operation is, of course, greatly complicated when the various members of one co-operative store trade or purchase articles in the various stores, since it is necessary that the purchases made by members be credited to the members irrespective of where the purchases are made.

The present machine, by virtue of the fact that a tabulating card is punched pertaining to each sale or transaction provides the original record for the determination of the necessary statistics. These tabulating cards are punched to represent the amount of the sale, the member number and other designations pertaining to the transaction and by means of the member number designation they are capable of being selectively sorted so that the transactions pertaining to each mem-

ber are sorted in a single group. By tabulating the various groups of cards, a tabulating machine will total the amount of sales for each of the different members. By means of other designations, such as clerk's numbers, store numbers, etc. the cards may be sorted into other groups for sales analysis according to other classifications.

It is, therefore, the main object of the present invention to devise an improved key-controlled machine which is capable of punching a tabulating card and in the same operation of the machine to print a record strip and also issue a check, and to print upon the record strip and issued check data pertaining to the transaction. The record strip, as is well known, is contained within the machine so as to provide an unchangeable record of all the transactions made therein. The checks issued by the machine contain the same data as on the record strip and are given to the customers as receipts of the transactions and may be utilized by them if they should question the totals of their purchases.

A further object of the invention, especially in connection with the punching mechanism, is to devise an improved means of construction of punch slides and an improved means for causing an operation of the punch pins of the punch slides and the positive retraction thereof at the termination of the punching operation.

A further object in connection with the card punching mechanism is to provide an improved form of card feeding device which will feed the cards with certainty and to accomplish efficient card feeding operations by mechanisms which are simple to construct and positive in operation.

The last mentioned object is obtained by causing the group of tabulating cards to be punched to be resiliently urged towards a feeding roller which upon its rotation engages and feeds through the punch mechanism the uppermost card of the stack.

A still further object of the invention in connection with the card feeding mechanism is the provision of means for depressing the stack of tabulating cards so that the aforementioned feeding roller can feed only a single tabulating card and not accidentally feed more than one card during the same cycle of operation of the machine.

A still further object of the invention is to provide a locking mechanism for the machine whereby the motor release bar which is operated to cause the operation of the machine cannot be

operated or depressed unless one of the clerk's keys is depressed.

The machine also includes a locking mechanism for locking each of the clerk's keys and, therefore, the motor release bar, whenever the machine senses an improper or faulty feeding operation of the card feeding mechanism and the object of the locking mechanism is to devise a common lock for the clerk's keys which is rendered effective (1) when the supply of cards in the supply hopper is exhausted and (2) when a card fails to feed from the supply hopper to the punching mechanism or is improperly positioned in the punching mechanism.

10 The provision of the aforementioned locking and interlocking mechanism requires the proper operation of the machine and thereby insures that each transaction entered in the machine is properly recorded and represented by a punched tabulating card.

15 While the invention has been shown in connection with a machine of the type previously described, any one or all of the improvements described herein may be utilized in connection with 20 a variety of machines and the present embodiment is to be considered merely as illustrative and not restrictive.

25 Further objects of the instant invention reside in any novel feature of construction or operation or novel combination of parts present in the embodiment of the invention described and shown in the accompanying drawings, whether within or without the scope of the appended claims and irrespective of other specific statements as to the 30 scope of the invention contained herein.

35 In the drawings:

40 Fig. 1 is a perspective view of the machine showing particularly the arrangement of the keyboard for effecting the entry of the items in the machine and other designations pertaining to the transaction.

45 Fig. 2 is a transverse sectional view taken at the left end of the machine and along the section line designated 2—2 in Fig. 1.

50 Fig. 3 is a detail sectional view taken on the section line 3—3 of Fig. 2 and shows the constructional details of the keys.

55 Fig. 4 is a detail view showing the interlock between the bank of clerk's keys and the motor release bar.

60 Fig. 5 is a view in side elevation showing some of the parts shown in Fig. 2 on an enlarged scale and shown in an operated position.

65 Fig. 6 is a transverse sectional view taken substantially through the central part of the machine.

70 Fig. 7 is a view in front elevation showing in detail certain parts of the interlocking mechanism of the machine and is taken on the line 7—7 of Fig. 2.

75 Fig. 8 is a sectional view taken on the section line 8—8 of Fig. 7.

80 Fig. 9 is a transverse sectional view, on an enlarged scale with respect to Fig. 6, and shows in detail the construction and operation of the printing mechanism for printing an issued check and a record strip contained within the machine.

85 Fig. 10 is a view in elevation of the back of the machine and is taken on the line 10—10 of Fig. 2.

90 Fig. 11 is a detail view of the parts associated with the clutch engaging mechanism and the means for initiating the operation of the motor of the machine.

95 Fig. 12 is a detail view of the operating connec-

tions for the check severing mechanism and the platen operating mechanism.

100 Fig. 13 is a detail view of the operating means for the record strip feeding device.

105 Fig. 14 is a detail view showing a train of operating gears and driving mechanism for certain parts of the check issuing mechanism.

110 Fig. 15 is a top plan view taken on the line 15—15 of Fig. 14.

115 Fig. 16 is a plan view of the card punching mechanism.

120 Fig. 17 is a detail sectional view taken on the section line 17—17 of Fig. 16 on an enlarged scale.

125 Fig. 18 is a longitudinal sectional view of the 11 punching mechanism taken on the section line 18—18 of Fig. 16.

130 Fig. 19 is a view in front elevation of the 12 punching mechanism taken on the line 19—19 of Fig. 16.

135 Fig. 20 is a longitudinal sectional view taken on the section line 20—20 of Fig. 16.

140 Fig. 21 is an illustration of one of the checks which is capable of being printed by the present machine.

145 Fig. 22 is a fragmentary section of the record strip which is printed by the present machine.

150 Fig. 23 is a view of a perforated tabulating card showing the manner in which perforations are made by the punching mechanism to represent 30 an item and designations pertaining to the item entered in the machine.

155 Fig. 24 is a timing diagram.

160 Fig. 25 is a detail view of one of the slides of the differential mechanism.

165 Figs. 26 and 27 are each combined views in side elevation and plan showing two constructions of punch slides.

Keyboard

170 The arrangement of the keyboard of the present machine is disclosed in Fig. 1 and the keys comprise a plurality of banks of depressible keys, which are depressible by the operator prior to a 40 cycle of operations of the machine so as to control certain functions.

175 The two keys designated 20 (Fig. 1) at the extreme right of the keyboard are two keys which control a printing or perforating means to designate the initials "F" and "D" representing the 45 clerks operating the machine.

180 The numerical value entries in the present machine are preferably made in accordance with the English monetary system and the value entries are controlled by a plurality of banks of keys comprising six banks and these keys are designated 50 by the reference numeral 21. The three keys at the extreme right of the six banks comprise keys for controlling the entry of fractional pence. The next bank of keys controls the entry of pence from the amount "1" to "11". The next two 55 banks of keys are for controlling the entry of shillings while the remaining two banks control the entry of pounds in the English monetary system.

185 At the left of the machine there is provided a keyboard comprising six banks of keys and five of these banks of keys 22 are utilized for controlling the entry of the "member number" which 60 comprises an account number of the customer making a purchase in the particular store in which the machine is utilized.

190 The bank of six keys designated by reference numeral 23 at the extreme left are for controlling the entry of the type of transaction.

Motive power for the machine

The motive power for the machine is derived from an electrical motor 25 (Fig. 10) which is set in operation to operate the various mechanisms by means of a motor release bar designated by reference numeral 24 (Fig. 1).

The armature shaft of the motor 25 is adapted through a speed reduction mechanism in a casing 26 (Fig. 10) to rotate a shaft 27 which carries a ratchet toothed clutch wheel 28 (see also Fig. 11). Through a clutch mechanism, now to be described, a drive shaft 29 is given a single revolution for each operation of the machine.

Referring to Figs. 10 and 11, the stem 30 of the motor release bar 24 is adapted by its manual depression to engage with a stud 31 carried by an arm 32 and rock said arm, and a sleeve 33 connected to said arm, in a counter-clockwise direction. To said sleeve there is secured an arm 34. Loosely mounted upon the sleeve 33 is a clutch control arm 35 which is in the plane of a clutch dog 36 pivotally mounted at 37 to a disk 48 secured to the aforesaid drive shaft 29. The arm 34 carries a stud having two diameters, 39 and 40, so that when the arm 34 is rocked the larger diameter 39 of the stud will engage a projection 41 of the clutch control arm 35 thereby rocking the clutch control arm so as to disengage its hooked end 42 from the clutch dog 36. A spring 43 will, thereupon, be effective to rock the clutch dog 36 so that a clutch tooth 44 thereof will engage one of the clutch teeth of the ratchet wheel 28 which is now at rest.

Upon a further rocking movement of the arm 34 the smaller diameter 40 of the stud carried by the arm 34 will engage one arm 45 of a bell crank so as to rock a hooked end 46 formed on another arm 47 of the bell crank out of engagement with a notch in the disk 48 secured to the aforementioned drive shaft 29. The disengagement of the hooked end 46 of the arm 47 will thereby unlock the shaft 29 for rotation. As the arm 34 is still further rocked the arm 45 of the bell crank will cause the closure of contacts 49 to thereby electrically connect the motor 25 to the current supply S, as shown in Fig. 11. The armature shaft will thereby rotate the ratchet wheel 28 through the speed reduction mechanism just described and through the clutch connection, which was previously made between the clutch dog 36 and the ratchet wheel 28, the shaft 29 will rotate together with the disk 48 and a supplemental disk 50. The proper operation of the machine requires that the operator withdraw his hand from the motor release bar so that the latter may be elevated to normal position by means of a spring, not shown, and this will permit a spring 51 connected to the arm 34 to rock said arm back to normal position. The arm 34 is provided with an extension carrying a lug 52 and to said lug and extensions 53 and 54 of the bell crank 45-47 and clutch control arm 35, respectively, there are connected individual springs 55. Obviously, when the arm 34 is rocked reversely to its normal position by means of the spring 51 the spring 55, connected between the lug 52 and the extension 54, will rock the clutch control arm 35 reversely so as to engage the extremity of the clutch dog 36 when a full revolution has been given to the shaft 29 thereby engaging the clutch dog 36 to cause it to be rocked to effect the disengagement of the clutch tooth 44 from the ratchet wheel 28 by a reverse action.

It is preferred to provide means for retaining

the contacts 49 closed during the engagement of the clutch and this is provided for by means of the disk 48.

It will be seen that when the hooked end 42 is disengaged from the notch of the disk 48 and the disk 48 thereafter rotated in a clockwise direction, the circular periphery of the disk 48 will retain the bell crank 45, 47 in rocked position thereby retaining the contacts 49 closed during the clutch engagement.

The safety disk 50 is also carried by the shaft 29 and is provided with a recess which includes an inclined cam edge 56. When the arm 34 is rocked an extension 57 of the arm 34 will enter in the notch of the safety disk 50 but upon the initial clockwise rotation of the disk 50 the cam edge 56 will coat with the extension 57 thereby rocking the arm 34, sleeve 33, and arm 32, in a counterclockwise direction positively forcing the stem 30 of the motor release bar to normal position. The concentric edge of the safety disk 50 prevents the motor release bar from again being depressed during the operation of the machine. Hence, the motor release bar 24 cannot be held down during the operation of the machine. Rocking of the arm 34 to normal, will, of course, through the spring 55 tend to rock the bell crank 45, 47 to normal to tend to open contacts 49 so as to open the circuit of the motor 25 but the engagement of the hooked end 46 of the arm 47 with the concentric edge of the disk 48 will keep the bell crank shifted to retain contacts 49 closed for a complete revolution of the shaft 29. Rocking of the arm 34 will merely stretch the related spring 55. The shaft 29 may be considered as the main drive shaft of the machine which operates various mechanisms thereof.

Keyboard construction

The details of construction of the keyboard will be explained and described in connection with Figs. 2 and 5 which disclose the keyboard arrangement for a single bank of keys. With the exception that the various banks of keys may vary in position and number, the construction of each bank is substantially identical.

The keys are of the usual key-set type and comprise key stems 58 (Fig. 3) provided with key caps 59 carrying indicia, such as numerals and letters, indicating the digit or character of the particular key. Each of the key stems 58 is slidably mounted in a U-shaped support plate 60 and 61 (see Fig. 3) and each of the keys is manually depressible against the action of a spring 62 which returns the key to normal after it has been released. Each of the key stems is provided with a wedge-shaped lug 63 adapted to catch underneath a detent plate 64 so as to retain the key in depressed position. Fig. 5 shows very clearly the manner in which a key is depressed and held in depressed position, this key being the "5" key of a bank.

It is desirable that the depressed key of a particular bank and all the undepressed keys be locked against manipulation during the operation of the machine and this is provided for by the following described means. Loosely mounted upon a rod 65 (Fig. 2) is a bell crank 66 having a projection 67 cooperating with a portion 68 of a cam 69 carried by the operating shaft 29. This relationship is effected by means of a spring 70 secured to one arm of a bell crank 66, which is connected to an arm 71 secured to a rock shaft 79 (Fig. 5) by means of a 75

link 72. Loosely mounted upon a rod 73 is a spring pressed ball 74 and one side of ball 74 is provided with an extension 75 coacting with a cam plate 76 which is secured to the rock shaft 79. At the initial operation of the machine the cam 69 is rocked in a clockwise direction, as viewed in Fig. 2, permitting spring 70 to be effective to cause the projection 67 to drop off the high part 68 of the cam 69 to rock the bell 10 crank 66 and to cause the link 72 to be depressed. This will rock the shaft 79 and cam plate 76 counterclockwise causing a projection 71 thereof to strike a side arm of the bail 74 and move as shown in Fig. 5 bail 74 to the rear of the extremity of all the detent plates 64 provided for each of the banks of keys. Locking of the detent plates 64 in this manner will prevent accidental release of the depressed key and also prevent depression of any of the unoperated keys 20 in all banks and this locking action is maintained during substantially the complete operation of the machine by virtue of the fact that the bail 74 will be maintained in its elevated position (see Fig. 5).

25 It is, of course, desirable to release the depressed keys at the completion of the operation of the machine and to effect this operation another high portion 78 of the cam 69 will, at the termination of the machine operation, rock the 30 bell crank 66 clockwise so as to elevate the link 72 and depress the bails 74 to unlock the detent plates. Attached to the shaft 79, to which the arm 71 and cam plate 76 are connected, is a bail 80 and said bail overlies a plurality of bell 35 cranks 81, the upward arm of which passes through an aperture in the related detent plate 64. By the depression of the bail 80 the bell cranks 81 will be rocked counterclockwise shifting each of the detent plates 64 rearwardly to 40 disengage the wedge-shaped lug 63 of the depressed key from the detent plate permitting the related spring 62 to restore it to normal position.

Differential mechanism

45 The differential mechanism will now be described in connection with Figs. 2 and 5 and the bank of keys disclosed therein, it being understood that the construction of the remaining banks is similar.

50 Attached to the drive shaft 29 is a pair of complementary cams 90 (Fig. 2) cooperating with follower rollers carried by an arm 91 loose on a stud 92. The arm 91 has an integral segment 93 meshing with a mutilated gear 94 secured to a rock shaft 95. To the rock shaft 95 there is secured a pair of double arms 96, the upper extending arms carrying a rod 97, and the lower arms carrying a rod 98.

55 A sector or gear segment 99 is supported by the rods 97 and 98 and thereby partakes of the reciprocating movement effected by rocking the double arms 96. The teeth of each of the pair of gear segments 99 mesh as shown in Fig. 25 with the teeth of a related one of a pair of rack slides 100, and each rack slide 100 is provided with a longitudinal guide slot 101 receiving a fixed guide rod 102 and a longitudinal guide slot 103 receiving a fixed guide rod 104. By any suitable mounting means the pair of rack slides support 60 and carry a transverse bar, there being provided a bar 106 for the six banks of keys at the left and by a similar construction of arms 96, rods 98, segments 99, slides 100, a bar 107 (Fig. 10) is reciprocated for the differential mechanism of 65 the seven banks of keys at the right (Fig. 1).

Obviously, referring to Figs. 2 and 5 the bar 106 is reciprocated for each operation of the machine being moved from right to left, and then left to right and for each machine operation an invariable amount.

Also slidably mounted on the guide rods 102 and 104 there is a supplemental rack slide 108, one for each key bank, and each of said rack slides 108 meshes with a related segment 109. Also mounted on the guide rods 102, 104 is a disengaging slide 110 (Fig. 3) and the slide 110 is mounted adjacent the slide 108. The slide 108 carries a pair of pins 111 received by slots formed in the adjacent disengaging slide 110 so that the disengaging slide 110 may move a slight amount independently of the related slide 108, for a reason to be made clearer later, and in this instance a spring 112 interposed between tongues carried by the slides 108 and 110 may be compressed. Namely, the slides 108 and 110 move 20 as a unit.

The slide 108 carries a pin 113 which is the pivot pin of a latching pawl 114 which is provided with a hook 115 (Fig. 2) normally catching over the rear edge of the bar 106. The pawl 114 25 has a slot receiving a lug 116 of the disengaging slide 110. In the normal position of the slide 108 a depending extension 117 of the slide 108 receives the forward edge of the bar 106 and together with the hook 115 it will be seen that 30 the slide 110 is latched to the bar 106 and thus is reciprocated by the bar 106. The compression of spring 112 acts to shift the slide 110 so as to be latched to the bar 106 and thus is reciprocated by the bar 106. The compression of spring 112 35 acts to shift the slide 110 a slight amount independent of the slide 108 thus maintaining by the lug 116 the rocking of the pawl 114 to cause the hook 115 to firmly catch over the rear edge of the bar 106. Obviously the movement of the 40 bar 106 to the rear will move the slides 108, 110 correspondingly thus positively rocking the related segment 109 in a counterclockwise direction until the slide 110 is stopped in a manner now to be set forth.

45 Referring to Fig. 3 it will be seen that the key stems 58 are provided with depending extensions 118 bent into four planes and that the slide 110 also is provided with upstanding extensions generally designated by numeral 119, and also bent in four planes to be correlated with the planes of the extensions 118 of the keys. This correlation is effected so that each key extension 118 will coact with its related stop extension 119 to determine and effect the proper differential movement of 55 the slides 110 and 108. For example, stop extension 119 will be stopped by the extension 118 of the "1" key, the stop extension 118 will be engaged by the extension 118 of the "5" key, as shown in Fig. 5, etc., the extensions being so arranged that the effective key extension 118 will coact only with the related extension of the slide 110.

50 When the extension 118 of a depressed key coacts with the related stop extension 119 the slide 110 will be positively stopped in its movement but latch pawl 114 will continue to move the slide 108, compressing the springs 112 and at the same time rocking the pawl 114 since it is held by the lug 116 to cause the hook 115 to be disengaged from the bar 106 so that an extension 120 of the pawl will catch under teeth of a bar 121, the cooperating teeth being so shaped as to maintain this relationship effected by the compression of 75

the spring 112. Bar 106 may now continue its movement to the rear.

In this manner the keys determine the differential movement given to slides 108 and the driven segments such as the segment 109, for the key bank disclosed in Figs. 2 and 5.

The segments 109 are maintained in their differentially set positions for a while to permit certain operations of the machine and thereafter the rod 97 will coat with these segments and restore them to normal. The bar 106 will, of course, also engage the extensions 117 of the slides 108 rocking the pawl 114 out of engagement with the teeth of the bar 121, and thereafter restoring the slides 108 and 110 to normal position shown in Fig. 2.

Printing mechanism

The differential movement communicated to the segments 109 is adapted to differentially set a series of punch pin carrying slides so as to punch a record, as well as type carriers to also print upon a record strip and an issued check. A portion of the record strip which is capable of being printed by the present machine is shown in Fig. 22 and Fig. 21 represents an issued check which is printed by the machine; it being noted that the line of data printed representing the item and other designations relating to the item entry in the machine is common for both the check and record strip and this common printing is effected by means of a single set of type carriers which are differentially set by connections now to be described.

It is understood that the six banks of keys at the extreme left in Fig. 1 are capable of differentially setting their related segments 109 and these six segments 109 are shown in Fig. 10, which is a back view of the machine. Each of said segments 109 is in continuous mesh with a related pinion 125 carried by a related shaft 126, these shafts extending transversely of the machine and being also provided at their extremities with pinions 127. There is, of course, a series of six shafts 126 so as to communicate the differential movement of the operating segments 109 to the pinions 127. From Fig. 6 it will be seen that one of the pinions 127 shown in this view is in mesh with a segment 128 which is double in form in that it is provided with upper teeth 129 and lower teeth 130. A set of six segments 128 is provided as best shown in Fig. 10.

A corresponding form of connection (see Fig. 10) is provided for the seven operating segments 131 (which are similar to segments 109) related to the seven banks of keys at the right of the machine and these seven segments 131 have corresponding connections through shafts and pinions to a set of seven segments 132 which are shown in Fig. 10 and are similar in construction to the segments 128.

It will be understood that the upper teeth 129 of each of the segments 128 are adapted to set a corresponding type carrier and an example of such connection for one type carrier is shown in Fig. 9 wherein it will be seen that the teeth 129 are in mesh with a pinion 133 secured to a type wheel 134 having printing characters upon its periphery. In this manner, the six operating segments 128 and the seven operating segments 132 are adapted to adjust a set of thirteen type wheels to print upon a record strip and an issued check. Each of the aforementioned type wheels are provided with printing characters comprising the same indicia that are provided upon the key caps 75 so that there may be printed upon the record

strip and issued check the character designating the clerk operating the machine, which is printed in the extreme right hand column, and in the next six columns to the left the amount of the transaction is recorded in the English monetary system. The type wheels 134 controlled by the five banks of keys 22 carry type so as to print the member's account number and this is preferably printed in distinguishing characters upon the record strip and issued check by small numerals, as shown in Figs. 21 and 22. The bank of transaction keys 23 causes the adjustment of a related type wheel 134 so that the record strip may be imprinted with alphabetical characters or abbreviations designating the type of transaction entered in the machine.

For the single bank of pence keys having eleven keys—1—9, 10 and 11, as shown in Fig. 1, there is provided a type wheel 134 having eleven corresponding type, as shown by numerals on the type wheel 134 shown in Fig. 9. The two extra keys "10" and "11" are shown dotted in Fig. 2 and the extension 118 of the key designated "11" coats with the stop extension 119, which prevents any appreciable movement of the slides 108, 110, and segments 109, and 128. The type "11" will thus be printed from. The extension 118 of the "10" key will coat with stop extension 119 to cause the movement of the related type wheel 134 one step to select the "10" type for printing.

For all the key banks having only keys 1—9 the type wheels are blank in the first two positions but the type wheels are rotated two steps to select the "0" type in the absence of the depression of a key in that bank. In this case the stop extension 119 will engage an extension 810 of the bell crank 80 of the bank in which a key is not depressed; since in this instance the bell crank 81 is not rocked. The keys 1—9 of banks having such digit keys, or correspondingly positioned keys, control the differential movement of the type wheels 3—11 steps, respectively to select the proper type for printing.

There will now be described the means for effecting the printing impression upon the issued check and upon the record strip contained in the machine, this being described in connection with Figs. 6, 9 and 12.

The record strip contained within the machine is designated in Figs. 6 and 9 by the reference numeral 135 and the record strip is drawn from a supply roll 136 and extends over a roller 137 (Fig. 9) thence over a roller 138 and to and around a roller 139, it being noted that this part of the record strip is directly beneath a platen 140. From the roller 139 the record strip extends upwardly and thence over a roller 141 to and around a roller 142, to a take-up roller 143. The take-up roller 143 is provided, as shown in Fig. 6, with a ratchet wheel 144 adapted to be engaged by a reciprocating pawl 145, the latter being connected at 146 to a bell crank 147. One arm of the bell crank 147 is forked to receive a stud 148 carried by a follower arm 149 (see Fig. 13) pivotally mounted at 150 and provided with follower rollers 151 engaging complementary cams 151 secured to the drive shaft 29. The complementary cams 151 cause, at the initial operation of the machine, the rocking of the bell crank 147 in a clockwise direction and the bell crank 147 in a counter-clockwise direction thereby drawing the pawl 145 downwardly so as to engage the teeth of the ratchet wheel 144 and rotate the take-up roller 143 so as to feed the record strip the extent of one printing line. This feeding operation will space 75

the imprint next to be effected from the succeeding imprint if it has been made. After the line spacing operation an impression is taken from the type wheels, while they are stationary, 5 upon the record strip by means to be presently described.

The inking ribbon is designated in Figs. 6 and 9 by the reference numeral 152 and is fed from one supply roll 153 to a storage roll 154 and to 10 effect this feeding operation any suitable step by step ink feeding means or ink ribbon reversing means may be provided. Such arrangements are common and well known in the art and for this reason will not be described.

15 From Fig. 9, it will be seen that the inking ribbon 152 is disposed between the type wheels 134 and the portion of the record strip between the rollers 138 and 139 so that when the platen 140 is depressed it will effect an impression upon 20 the record strip. The platen 140 is adapted to be reciprocated twice, once for effecting the printing upon the check paper in the manner to be presently described, and the second time upon 25 the record strip and this latter operation is adapted to occur as shown in the timing diagram in Fig. 24 in the period of the cycle designated as "Record strip print" during which time it will be seen that the type wheels 134 are also in stationary adjusted position.

30 The platen 140 is carried by a pair of arms 155 secured together by a tube 156 loosely overlying a shaft 157 (see Fig. 9). One of the arms 155 is provided with a rearward extension 158 (Figs. 6 and 12) provided with a pin 159 engaging a 35 forked extension of an arm 160 pivoted at 161. The rearward extension of the arm 160 is connected to an arm 162 by means of a link 163 and the arm 162 is secured to a rock shaft 164. To the rock shaft 164 (Fig. 12) there is secured a 40 follower arm 165 cooperating with complementary cams 166 secured to the drive shaft 29.

By the above described connection between the platen carrying arms 155 and the complementary cams 166, the latter will reciprocate the 45 platen 140 twice during each machine operation, and during the second reciprocation the platen 140 will force the record strip against the inking ribbon 152 so that the type wheels will effect a printing impression upon the record strip.

50 The check paper which is imprinted to form the check designated by reference numeral 171 (Fig. 21) is drawn from a supply roll 172 and is led over a guide plate 173 and between an electro roller 174 and a platen roller 175. The platen 55 roller is carried by a spring pressed frame 176 (Figs. 6 and 9) and this frame is also provided with a resiliently urged inking roller 177 which inks the electro type carried by the electro roller 174. When the electro roller 174 is rotated it 60 will feed the record strip and at the same time imprint upon the check paper the three lines of data designated by the reference numeral 178 (see Fig. 21).

Attached to the drive shaft 29 (Fig. 14) is a 65 gear 179 adapted to drive a pinion 180 through a series of idler gears 181. Attached to the gear 180 is a gear 182 which is in mesh with a gear 183 and the gear 183 has attached thereto a mutilated gear 184 and a supplemental mutilated 70 gear 185. By the above described gear connections the gear 183 and mutilated gears 184 and 185 are given a complete rotation for each operation of the machine. The shaft 186 carrying the electro roller 174 has secured thereto a pinion 75 187 (Fig. 14) which is adapted to be engaged by

the teeth of the mutilated gear 184. The teeth of the mutilated gear 184 are disposed in an arc designated "A" in Fig. 14 and are so disposed that at the initial operation of the machine, the counterclockwise rotation of the mutilated gear 184 will cause its teeth to engage the pinion 187 thereby driving the electro roller 174 in the period of the operating cycle shown in the timing diagram in Fig. 24 and designated "Check feed." This feeding of the check paper corresponding to the length of the checks occurs substantially during the time that the type wheels 134 are being differentially set during which time the check paper is fed so as to be disposed over the inking ribbon 152 and beneath the record strip 135 so that the first depression of the platen 140, in the manner previously described, will effect an imprint only upon the check paper.

15 After the imprint has been effected, the printed check paper will be fed out of the machine between a pair of guide plates 188 and 189 (Fig. 9), it being noted that the check paper during the check feeding operation will be fed beneath a flattened portion of a check feeding roller 190 which is secured to a shaft 191.

20 Referring to Fig. 14, the mutilated gear 185 is in the plane of an idler gear 192 which meshes with a pinion 193 secured to the shaft 191 and the teeth of the mutilated gear 185 are provided in an arc designated B in Fig. 14 and are so disposed as to engage the idler pinion 192 to rotate the pinion 193 and the shaft 191 during the operating period of the machine designated in the timing diagram as "Eject."

25 When the check strip was fed during initial operation of the machine the leading portion was disposed beneath the flattened portion of the check feeding roller 190 and the resilient plate 189 so that the cooperation of the circular periphery of the roller 190 with the resilient plate 189 will feed the check strip out of the machine 30 and through an aperture 194 (see Fig. 1) of the cabinet so that it may be grasped by the operator and withdrawn from the machine.

35 The machine is also provided with a cutting or severing device for severing the printed portion of the check paper from the remaining part of the roll and this is provided for by a movable knife 195 and a fixed knife blade 196 (see Fig. 9), it being noted that the check paper passes between these knife blades.

40 The movable knife blade 195 is carried by the forked ends of a pair of arms 197 (see Fig. 12) secured to a rock shaft 198 and to said rock shaft 198 there is secured an arm 199, it being noted 45 that the stud 159 is also a pivotal connection between the arm 199 and the arm 160. By the above described operating means it will be seen that each time that the platen 140 is depressed the arm 199 will be rocked clockwise and the 50 movable knife blade 195 will be depressed at the same time. It will be recalled that the platen is operated twice but during the first depression of the platen the check strip will be severed by the movable blade 195 after which time the 55 printed check will be ejected from the machine and out of cooperation with the movable knife blade 195 and the platen 140. The second depression of the platen 140 will cause the printing 60 upon the record strip, since at this time the check paper is entirely out of cooperation with the platen 140, and obviously during the second depression of the movable knife blade 195 no effective severing operation will take place.

Punching mechanism

The parts of the punching mechanism are primarily carried by a box-like frame comprising a bottom plate 201 (Fig. 16), a side plate 202, a parallel side plate 203, and two end plates 204 attached to the base plate 201 and the side plates 202 and 203 so as to provide a rigid box-like frame.

The stack of tabulating cards 205 (Fig. 18) to be punched are contained in the machine between the side plates 202, 203 and plates 206 and are fed singly from the top of the stack by means to be presently described. The plate 202 carries outside of the card receiving receptacle a pair of guide bars 207 (Figs. 16, 18 and 20) and which are guide bars for rollers 208 carried by a plate 209, said plate 209 being provided with an integral transverse plate 210 to which is attached a bottom support plate 211 on which the stack of tabulating cards rests. In order that the stack of tabulating cards may be moved freely upward the bottom support plate 211 is provided with rollers 212 (Fig. 18) rolling along the inside of the side plate 202. A spring 213 (Figs. 18 and 20) is connected at one end to a stud 214 carried by the plate 209 and passes around a pulley 215 and the other end is attached to a fixed rod 216 and the tendency of the spring is to elevate the plate 209—210, and the bottom support plate 211 thereby continually urging the stack of tabulating cards upwardly so that the uppermost card frictionally engages the periphery of a feeding roller 217 (Fig. 18) which is secured to a shaft 218.

The driving shaft for operating most of the operating devices of the card punching mechanism is designated by reference numeral 219 (Figs. 18 and 20) and to said shaft there is connected a beveled gear 220 (Fig. 16) in mesh with the beveled gear 221 attached to the main drive shaft 29 whereby the drive shaft 219 of the punching mechanism is given a complete rotation for each machine cycle. To the shaft 219 there is connected a gear 222 (Fig. 20) in mesh with a pinion 223 attached to a larger gear 223a which is in mesh with a pinion 224 secured to a shaft 225. The pinion 224 is in mesh with a pinion 226 secured to a shaft 227. The pinion 226 drives a gear 228 through an idler pinion 229, and said gear 228 is secured to the shaft 218. Through the train of gears just described and shown in Fig. 20 the drive shaft 219 will rotate the shaft 218 thereby causing the roller 217, which is preferably formed of rubber, to rotate in a counterclockwise direction as shown in Fig. 18. By its frictional contact with the uppermost card it will feed said card to the right, as shown in Fig. 18, until said card is between the roller 217 and a roller 230 secured to the shaft 227. The rollers 217 and 230 in cooperation with each other will feed the card further to the right until said card passes between a roller 231 attached to the shaft 225 and spring urged rollers 232. The rollers 232, of which there is a pair, are each carried by a frame loosely pivoted upon the rod 233 and to the frame there is secured a spring 234 normally urging the roller 232 to contact the roller 231. The rollers 231 and 232 thereby feed the card to the right, as viewed in Fig. 18, until the leading edge of the card being fed passes between rollers 235 and spring urged rollers 236, the latter being arranged, constructed and supported similar to the rollers 232.

From Fig. 20 it will be seen that the gear 222 is in mesh with a pinion 237 secured to a gear 238 and said gear meshes with a pinion 239 attached

to a shaft 240 to which rollers 235 (Fig. 18) are secured. The feeding of the card to the right, as viewed in Fig. 18, is terminated by means of a plate 241 which acts as a card stop and said plate is slidably mounted in a U-shaped support plate 242 and the plate 241 is apertured so as to receive a pair of arms 243 attached to a shaft 244.

Attached to the drive shaft 219 is a cam plate 245 (Fig. 20) cooperating with a double arm 246 and the upper arm engages a stud 247 carried by one arm of a bell crank 248 secured to the shaft 244. The configuration of the cam 245 is arranged to rock the double arm 246 at the initial operation of the machine thereby rocking the bell crank 248 in a counterclockwise direction, and the shaft 244 in the same direction, causing the plate 241 to be immediately depressed so as to be in the path of the card being fed. When the leading edge of the card, which is fed, abuts the stop plate 241 it will be entirely clear of the rollers 217 and 230 and 231—232 but the card will still be in coaction with the cooperating rollers 235—236, and said rollers are still rotating to tend to feed the card further to the right by a frictional driving engagement but will be unable to feed the card due to the depressed position of the stop plate 241. The card is thereby held in a proper position for a punching operation to be effected by means to be later described.

It will be observed that the roller 217 does not stop in its rotation during the operation of the punching mechanism of the machine, and if no means were provided the roller 217 would frictionally engage the card just beneath the one which is fed when the latter is fed clear of the roller 217. To prevent this operation, which would result in piling up of cards in the card punching mechanism, the following means is provided. Attached to a short stud 250 (Fig. 18) is an arm 251 carrying a stud 252 which is positioned in the card supply hopper so as to overlie the stack of tabulating cards to be fed. Attached to the stud 250 is a short arm 253 (Fig. 20) having a connection with a slidably mounted plate 254 which carries a roller 255 engaging a profile cam 256 secured to the drive shaft 219 of the punching machine.

From the timing diagram, shown in Fig. 24, it will be seen that the cam 256 is so timed that after the roller 217 has frictionally fed a card so as to be firmly engaged with the roller 217 and the roller 230, the cam 256 will shift the slide 251 to the left (Fig. 20) rocking the arm 253 and stud 250 in a clockwise direction thereby causing the arm 251 to be depressed from the position shown in Fig. 18. The roller 252 will engage the card which is being fed forcing the stack of tabulating cards downwardly and when the card which is being fed is clear of the roller 252, it will be seen that the roller 252 will now rest upon the upper surface of the card just below the one which is fed. The depression of the arm 251 will retain this card out of engagement with the roller 217 so that, even while the latter is still being rotated, it will not permit a second card feeding operation in the same machine operation. The cam 256 is arranged to retain the stack of tabulating cards depressed substantially during the rest of the machine operation after the time it is lowered. The tabulating card now having been fed to the proper punching position there will now be described the means for effecting the punching operation.

The punching mechanism is capable of punching the tabulating card, as shown in Fig. 23, so

as to designate by perforations the different data, such as the date, the type of transaction, member number, branch and department numbers, the amount of the entry and the clerk operating the machine. The card to be punched is preferably of the type shown in the patent to C. D. Lake, Patent No. 1,772,492, dated August 9, 1930. The rectangular perforations are made in columns, one in each column, and its location in the column indicates the digit, and perforations are also made at "10" and "11" index point positions to represent pence. For example, the member number punched represents—53421. The clerk operating the machine and the type of transaction are designated by a number code.

It will be recalled that the segments 128 are provided with segment teeth 130 (Fig. 6) which mesh with teeth of rack slides 257 which are slidably mounted in the machine. Each rack slide 257 has a longitudinal slot 258 (Fig. 26) in which the card to be punched passes. Each rack slide 257 is provided at its side above the slot 258 with a rectangular open notch 260a receiving a rectangular punch pin 259 and below the slot 258 at its side a rectangular die or open notch 260b registering with the rectangular punch pin 259. Details of construction of the punch slides will be given later.

It is explained that for the segments 128 and 132, which are set under control of the various key banks, the correlated rack slides 257 are moved differentially the same steps of movement as the type wheels, so as to position the punch pins 259 laterally over the card to the proper index point position. At this time the punch pins 259 are depressed by mechanism now to be described.

At this time, it is explained that the machine is provided with two supplemental rack slides 261 (Fig. 6) constructed like the other described slides but provided with finger pieces 262 (Fig. 16) by means of which these two slides 261 may be manually positioned along a scale 263, so that the punch pins will be positioned at index points to represent digits corresponding to the setting of these slides. These two slides are adapted to punch the two columns designated "Date" (Fig. 23) so as to represent the day of the month pertaining to the transactions entered in the machine during that daily period. A series of five punch slides 325 (Figs. 10 and 19) are centrally located between the separation of the two groups of slides 257 and are set at the factory so as to punch the branch and department number on all cards. From Fig. 10 it will be seen that these slides are accommodated in the space provided between the group of segments 128 and 132.

The two rack slides 261 are also in mesh with a pair of segments 264 (Fig. 10) which are similar to the segments 128 and 132 and these two segments are adapted to adjust item type wheels which print both upon the check to be issued and the record strip the digits selected by the setting of the slides 262. In Figs. 21 and 22 the printing of the date will be seen by observing the first two digits "12" from the left.

A shaft 265 (Figs. 16 and 18) is carried by parallel side frames 266 and said side frames are carried by the supporting frame plates 202 and 203. A punch operating frame plate comprises a bottom plate 267 and two integral side plates 268 and 269, each of which carries a pin 270 received by the forked end of a related arm 271 secured to the shaft 265. Each of the studs 270 extends through the related side plate 268 or

269 and into a bar 272 fitting in a related longitudinal guide slot made in each of the side frames 266 so as to provide a guide means for the reciprocating movement of the punch operating frame plates.

Attached to the operating shaft 29 is a pair of complementary cam plates 273 (Fig. 6) coacting with follower rollers carried by a follower arm 274 and said arm carries a stud 275 receiving the forked end of an extension of one of the arms 271. Each punch pin 259 has a transverse pin 276 (Fig. 6) overlying punch retracting bars 277 carried by downturned portions 278 of the punch operating frame to hold the punch pins 259 upwardly for free feeding of the card in the slot 258 and for also retracting the punch pins after the punching operation.

After the differentially adjusted punch slides have been set it will be seen from the timing diagram (Fig. 24) that when the punch slides are stationary the cams 273 will be effective to rock the arm 274 (Fig. 6) clockwise and through the arms 271 depress the punch operating frame, so that the lower surface of the plate 267 will strike the top ends of all the punch pins 259, thereby forcing them through the card and into the die apertures 260b. The punch operating frame is then elevated and the punch retracting bars 277 will positively move the pins out of the holes in the punched card.

An aligning bar 279, best shown in Fig. 17, is carried by the punch operating frame and engages aligning notches 280 of all of the rack slides to align the latter prior to punching operations and this aligning operation is effected when the rack slides are stationary.

After the punching operation the card stop plate 241 (Fig. 18) is elevated bringing it out of coaction with the card fed to the punching mechanism, thereby freeing the card for a further feeding now to be effected by the feed rollers 235—236 so as to feed the perforated card into the storage hopper 281.

While the above described mechanism is practically operative it is preferred to equip the machine with other devices which are in the nature of precautionary devices for preventing possible mis-operations of the machine. These devices will now be described in detail.

It will be recalled that the two punch rack slides 261 are manually set by the operator so as to predetermine the date designation to be made upon the card and printed upon the record strip and issued check. It is preferable to align and hold these in their adjusted position and this is effected by means of slidably mounted locking elements or pins 282 (Fig. 17) which are slidably mounted between plates 283 and said locking elements have head portions 284 which can be engaged by a finger so that the locking pin will be moved out of engagement with an aligning notch 280 permitting the free adjustment of the slide 261. When the slide is properly positioned a spring 285 (Fig. 19) will be effective to rock an arm 286, and since said arm engages the top ends of the locking elements 282, it will be seen that they will be positively depressed to engage the aligning notch 280 thereby preventing the accidental movement of the punch slides 262 out of their adjusted position.

The slides 325 are also provided with similar locking elements 326 (Fig. 16) but access to these cannot be had as it is desirable to lock them in their adjusted positions at the factory, or place of adjustment.

It is pointed out that the rack slides are so mounted side by side that they are normally not tightly pressed against each other permitting sufficient clearance so that they may be independently adjusted and without the use of a great deal of force. This looseness may cause the punching in the columns to be effected out of alignment and since it is necessary that the perforations are placed in exact column alignment, 10 and at the precise index point positions, a means for insuring this alignment is provided and will now be described.

Referring to Fig. 18 it will be seen that a shaft 287 has secured thereto a pressure plate 288 and a lower shaft 289 has secured thereto a pressure plate 290, and from Fig. 19 it will be seen that to the shafts 287 and 289 there are secured bell cranks 291 which are in the form of intermeshing segments and between said bell cranks 20 there is extended a spring 292. The spring 292 is normally tensioned so that, unless restrained, it will rock both shafts 287 and 289 to cause the pressure plates 288 and 290 to press against the rack slides firmly clamping and squeezing 25 them together.

This operation to permit the free positioning of the rack slides is normally allowed by means of a bell crank 293 (Fig. 18) which is formed as a latch engaging an arm 294 secured to the shaft 30 289. The bell crank will normally latch the pressure slides 288 and 290 and the unlatching thereof is effected by means of a pin 295 carried by a disk 296 secured to the shaft 219. When the disk 296 rotates, in the clockwise direction shown 35 in Fig. 18, the pin 295 will strike the arm 291 of the bell crank 293 thereby unlatching it from the arm 294 permitting the spring 292 to rock both shafts 287 and 289 to cause the pressure plates 288 and 290 to clamp the adjusted rack 40 slides. It will be noted that from the timing diagram (Fig. 24) this operation is effected when the punch slides have been differentially adjusted and are in stationary position.

When the rack slides are clamped or squeezed 45 they are forced against the U-shaped plate 242 (Fig. 18) previously described and a supplemental U-shaped plate 301.

It is further desirable to relatch the pressure plates 288 and 290 and this is effected by the following described means. A pin 298 carried by the arm 294 is received by the forked end of an arm 299 and said arm is engaged during the clockwise rotation of the shaft 219 by a cam 300, said cam being arranged to engage the arm 50 299 rocking it in a clockwise direction and the arm 294 and shaft 289 in a counterclockwise direction to cause the pressure plate 290 to be moved away from the rack slides. In the manner previously described, the pressure plate 288 55 will also be rocked to be simultaneously moved away from the adjusted rack slides.

When the cam 300 rocks the arms 299 and 294 the pressure on the rack slides will be released, as stated, and the pressure plates 288 and 290 60 will again be held in latched position by the bell crank 293 catching over the arm 294 permitting the subsequent free restoration of the rack slides.

70 Interlock between motor release bar, clerks' keys, and transaction keys

It is desirable to prevent the depression of the motor release bar 24 until one of the clerks' keys 20, in the key bank at the extreme right, 65 and a transaction key 23, in the key bank at the 70 75

extreme left, in Fig. 1 are depressed. The details of construction are shown in Figs. 2, 4, 6 and 7.

The stem of the motor release bar 24 is provided with a notch 82 (Fig. 4) normally engaged by one arm of a spring pressed bell crank 83. The detent plate 64 of the clerks' bank of keys is provided with a notch receiving one arm of the bell crank 83. Obviously, when one of the clerks' keys is depressed and locked in depressed position, the detent plate 64 will be shifted to the left, as shown in Fig. 4, in the manner previously described, so as to rock the bell crank 83 withdrawing one arm thereof out of coaction with the notch 82 thereby releasing the motor release bar 24 for a depression.

Referring to Fig. 8, it will be seen that the detent plate 64 of the clerks' bank of keys has a downturned portion 320 which is normally engaged by a shoulder 321 of a locking arm 322 which is pivoted upon a stud 323 and said arm is urged by a spring 324 to effect the normal locking relationship shown in Fig. 8. By the means just described the clerks' keys are normally locked against operation and these keys are released by first depressing one of the transaction keys 23.

As is best shown in Figs. 2 and 7 the detent plate 64 of the transaction bank of keys is also provided with a downturned portion 326 which is engaged by an arm 327 secured to a rock shaft 328. When one of the transaction keys is depressed the rearward movement of the detent plate 64 will cause by the engagement of arm 327 with the downturned portion 326 of the detent plate 64 the rocking of the shaft 328 thereby rocking an arm 329 (Fig. 8) secured to the rock shaft 328. The arm 329 is provided with a pin 330 engaging a cam edge 331 of the locking arm 322, so that when the shaft 328 is rocked the pin 330 will engage the cam edge 331 to rock the locking arm 322 counterclockwise to disengage the shoulder 321 from the downturned portion 326 of the detent plate 64 of the clerks' bank of keys. Since the transaction key, which is depressed, will remain in latched position the rock shaft 328 will also remain in its rocked position thereby unlocking the detent plate 64 of the clerks' bank of keys. The selected key of the clerks' bank of keys may now be depressed, and thereafter, the motor release bar may be depressed to initiate an operation of the machine.

By the above described means, the interlocking mechanism just described requires first the depression of a transaction key, then a clerks' key, and then the depression of the motor release bar 24.

Means for locking machine if a card has not been properly fed

The machine is preferably supplied with a locking mechanism which will prevent an operation of machine in the event that a card has not been properly fed in the punching mechanism, or if the card fed is improperly placed in the punching mechanism the same locking mechanism will be effective.

Referring particularly to Fig. 19, an arm 302 is secured to the rock shaft 244 and therefore said arm is rocked during the punching operation. 70 On the shaft 244 there is loosely mounted a double arm which comprises a feeler portion 303 and an integral extending arm 304. A spring 305 is interconnected between the arm 302 and 75 80 85 90 95 100 105 110 115 120 125 130 135 140 145 150 155 160 165 170 175 180 185 190 195 200 205 210 215 220 225 230 235 240 245 250 255 306 to engage a stud 307 carried by the arm 304. By virtue of this construction arm 302 and the feeler 303 move together as a unit when the arm 302 is rocked by the shaft 244. The free end 5 of the feeler 303, during its rocking movement, is adapted to engage with a card fed in the punching mechanism and if a card has been fed and properly presented therein, the movement of the feeler 303 will be stopped, but the arm 302 10 will continue to be rocked and in this operation spring 305 will merely be stretched. In this event an arm 308 which is an extension of the arm 304 will not be raised sufficiently so as to engage stud 309 and rock a cam plate 310 carrying said stud. 15 If a card has not been fed, or properly positioned in the punching mechanism, the feeler 303 will rock sufficiently, in the absence of the cooperation with the card, so that the arm 304 will 20 rock with the arm 302 causing the arm 308 to be rocked a maximum amount and by its cooperation with the stud 309 will rock the cam plate 310.

Attached to a rock shaft 311 is an arm 312 25 having a stud 313 engaging the cam plate 310. It will be seen that when the cam plate 310 is rocked counterclockwise the stud 313 will fall off the high portion to a low portion causing a spring 314 attached to the arm 312 to rock the shaft 311. The rocking of the shaft 311 will rock an 30 arm 312 secured to the rock shaft 311 and pass in front of an arm 315 (see Fig. 6) secured to the rock shaft 328. This will cause the rock shaft 328 to be locked, and in this instance, 35 the transaction keys 23 are locked so that none of these keys, the clerks' keys nor the motor release bar 24 can be depressed. This will prevent further operations of the machine until the cause of the improper feeding has been investigated. 40

From Fig. 1 it will be seen that the cabinet of the machine has a hinged cover 333 by which means of access of the punching mechanism may be provided. This will give access to the cam plate 310 (Fig. 19) which may be manually rocked so as to be brought back to the normal position thereby unlocking the transaction keys. 45

Construction of punch slide

Fig. 26 illustrates one construction of a punch slide that may be utilized. It will be seen that the punch slide 257, made of soft steel, is provided with an open notch 260_a in which fits the rectangular punch pin, and an open die notch 260_b. These notches are machined in the sides of the slides and to a depth of more than half the thickness of the slide. This materially weakens the slide at the thickness 257_a but this may be overcome by hardening the slide at the reduced thickness and the shaded area surrounding the notches 260_a, 260_b, but experience has shown that the hardening process usually causes some of the slides to warp, thus preventing the proper alignment of the punch pins. If the plate is bent too much bending will obviously take place at the part 257_a, and repeated bendings may cause breakage of a slide. 65

Fig. 27 illustrates a much preferred construction and comprises a relatively thin sheet of spring steel 240, which is machined to form the teeth 240_a, the aligning teeth 240_b, and the card receiving slot 258. Attached to the face of the spring steel sheet 240 by rivets 241, are plates 242, and these are separated so as to form the punch pin receiving aperture 260_a, and the die

aperture 260_b. These plates 242 can be hardened at the shaded portions to prevent wear by the punching operations. Since the sheet 240 is springy the slide may be bent in and out of its normal plane but will always return to this position. 5

In both constructions it will be seen that the adjacent slide covers the punch pin receiving notch 260_a and die notch 260_b thereby confining the pin in the slide. The squeezing or pressing 10 together of the slides causes the pins to be properly positioned in the slides, and the clamping together of these slides will cause the punching mechanism to be in effect a single rigid unit, and this construction will effect punching in proper 15 column postions.

While there has been shown and described and pointed out the fundamental novel features of the invention as applied to a single modification it will be understood that various omissions and 20 substitutions and changes in the form and details of the device illustrated and in its operation may be made by those skilled in the art without departing from the spirit of the invention. It is the intention, therefore, to be limited only as 25 indicated by the scope of the following claims.

What is claimed is:

1. In a card punching machine, in combination, a plurality of sets of manipulative devices, selected one of said manipulative devices being 30 presettable prior to an operation of the machine, differential mechanism controlled thereby, a plurality of punch pin carrying bars settable by said differential mechanism comprising for each bar a single punch pin and a correlated die aperture 35 oppositely disposed of a closed card receiving slot in said bar, an operating means for said machine including a normally locked motor release bar therefor, means controlled by one of said sets of manipulative devices for unlocking said motor release bar, devices for normally locking said last named set of manipulative devices, means controlled by the other of said set of manipulative devices for disabling said last named locking devices, a card sensing lever operated for each 40 operation of said machine to coact with cards fed to said punching pins to determine if a card is fed, or properly positioned for a punching operation, and means rendered operative by said card sensing lever in response to the 45 improper feeding of a card, or absence of a card being fed, to prevent said other set of manipulative devices from disabling said locking devices to prevent further operations of the machine. 50

2. In a punching machine, a plurality of differentially adjusted slotted punch slides, each carrying punch pins at one side of the closed slot for punching at predetermined positions on a card, and at the other side of the slot a co-operating die recess, and a plurality of aligning 60 notches, an aligning bar, means for operating said aligning bar to be received by said notches, a plurality of individually releasable elements received by said notches of said bars, and a resiliently urged plate engaging said locking elements 65 for retaining said locking elements in cooperation with the notches to maintain the adjusted position of said bar. 70

3. In a punching machine, in combination, a plurality of differentially positionable punch pin carrying bars, each provided with a slot receiving a card to be punched and each carrying opposite the slot a single punch pin and a co-operating die aperture, said bars being adjacently mounted but being individually freely positionable, means for 75

5 operating said pins to punch a card, means for clamping said bars together prior to an operation of said last named means to align said punch pins with the columns of the card, means for latching said clamping means during the punching operation, and means for thereafter disabling said latching means to enable said bars to be free for subsequent individual adjustment.

10 4. In a punching machine, a plurality of adjacently mounted differentially positionable slides, each provided with a closed card receiving slot, and open notches on opposite sides of the slot and formed in the side of the slide, one of which is a die aperture and the other an aperture which carries a punch pin fitting therein, and means for mounting said slides so that a slide covers the open side of each of the notches formed in an adjacent slide.

15 5. A punching element for a punching machine comprising a differentially settable punch slide having an elongated closed card receiving slot, and a plurality of open rectangular notches formed in one side of the slide and on opposite sides of the slot, one of said notches forming a die aperture, and the other of said notches receiving a rectangular punch pin fitting therein.

20 6. A punching element for a punching machine comprising a series of adjacently mounted differentially set punch slides each of a width corre-

sponding to a card column, and having an elongated closed card receiving slot, and also provided with a plurality of rectangular open notches on opposite sides of the slot, one of said notches forming a die aperture, and the other of said notches loosely receiving a rectangular punch pin, said slides being relatively free for differential adjustment and close together when punching is to be effected, whereby punch pins will perforate said columns at predetermined positions for machine control purposes.

25 7. A punching element for a punching machine comprising a sheet of resilient material formed with a closed card receiving slot, and carrying at its side a pair of relatively thicker plates of non-resilient material which are separated to form an open die aperture and an open aperture receiving a punch pin, said apertures being formed on opposite sides of the slot.

8. A card punching element for a punching machine comprising a sheet of resilient material formed with a closed card receiving slot, and carrying at its side a pair of relatively thicker plates of non-resilient material, which are separated to form at opposite sides of the slot a die slot and a punch pin receiving slot, said plate and sheet comprising in aggregate thickness the width of a card column.

FREDERICK L. FULLER.
